UNITED STATES PATENT OFFICE.

JOSEF DAUBEK, OF VIENNA, AUSTRIA-HUNGARY, ASSIGNOR TO MILLS & GIBB, OF NEW YORK, N. Y.

DESIGN FOR A CURTAIN AND COVER.

SPECIFICATION forming part of Design No. 19,262, dated August 13, 1889.

Application filed July 22, 1889. Serial No. 318,326. Term of patent 3½ years.

To all whom it may concern:

Be it known that I, JOSEF DAUBEK, of Vienna, Austria-Hungary, have invented and produced a new and original Design for Curtains and Covers, of which the following is a specification, reference being had to the accompanying photograph, forming a part thereof.

The leading feature of the design consists of the panel A, constituting two side and one end border, the panel B, constituting the other end border, the field C, inclosed by the panels, and the panel D, drawn upon the field.

The accompanying photograph illustrates a plan view of the design.

The panel A is made up of a series of snail-like rustic figures *a*, arranged to form a continuous scroll. The panel B consists, primarily, of a series of heart-like figures *b*, appearing to rest upon a trefoil figure *b'*.

Upon the field C a series of miter-like fig-

ures *C'* are drawn, represented as supported by basket-like figures *C²*, having arranged between them small cross-like figures *C³*.

The field-panel D is drawn in imitation of rustic snail-like scrolls *d*, corresponding with those in the panel A, grouped to form a trefoil figure, which trefoil figure appears to be supported by a base figure E, having as its principal characteristics two leaf-like scrolls arranged one at each side of the central figure E', resembling a pansy-leaf resting upon a clover-leaf.

I claim—

A design for curtains and covers, substantially as herein shown and described, and as per attached photograph.

Vienna, June 7, 1889.

JOSEF DAUBEK.
